UNITED STATES PATENT OFFICE.

ALBIN ERNST, OF CHEMNITZ, GERMANY, ASSIGNOR TO THE FIRM OF SCHUBERT & SALZER MASCHINENFABRIK, AKTIENGESELLSCHAFT, OF CHEMNITZ, GERMANY.

LOCKING DEVICE FOR THE NEEDLES OF CIRCULAR-KNITTING FRAMES.

1,172,691.

Specification of Letters Patent.

Patented Feb. 22, 1916.

Application filed March 27, 1914. Serial No. 827,712.

To all whom it may concern:

Be it known that I, ALBIN ERNST, a citizen of the German Empire, residing at Chemnitz, in the Kingdom of Saxony, Germany, have invented certain new and useful Improvements in Locking Devices for the Needles of Circular-Knitting Frames; and I do hereby declare the following to be a full, clear, and exact description of the invention, such as will enable others skilled in the art to which it appertains to make and use the same.

My invention relates to improvements in locking devices for the needles of circular knitting frames.

When performing the narrowing operation in circular knitting frames provided with rocking jacks the separate needles are thrown into or out of operation by means of the rocking jacks which are adapted to shift the lower ends of the coöperating needles in axial direction relatively to the cylinder. If the thickness of the jacks or the needles is not exactly alike, so that there is a certain clearance in the bearings of the same, or if some of the parts are bent out of their correct positions, there is a liability of the rocking jacks and the needles getting out of engagement with each other, one or more of the needles engaging in the jack which is adjacent to the proper jack. Thereby the parts of the machine are liable to break.

The object of the improvements is to so construct the needles and coöperating jacks, that this objection is removed.

With this object in view my invention consists in providing means for closing the jacks at their sides, so that the needles are always carried along in a reliable way and can not get out of engagement with the proper jacks.

For the purpose of explaining the invention an example embodying the same has been shown in the accompanying drawing, in which the same letters of reference have been used in all the views to indicate corresponding parts.

In said drawings Figure 1, is a side view showing the jack and the locking member on an enlarged scale, Fig. 2, is a horizontal section taken on the line A—B of Fig. 1, Fig. 3, is a side view similar to that shown

in Fig. 1 and showing the jack in connection with the coöperating needle, Fig. 4, is a horizontal section taken on the line C—D 55 of Fig. 3 and showing two adjacent jacks and the needles coöperating therewith, Fig. 5, is a side view similar to that shown in Fig. 3 and illustrating a modification of the invention, Fig. 6, is a horizontal section 60 taken on the line E—F of Fig. 5.

Referring to the example illustrated in Figs. 1 to 4, the jack *a* is in the usual form, and it is formed in its upper arm with a slot *e*. Near the upper end of the upright 65 arm *a'* and to one side thereof a plate *c* is secured by suitable means such as rivets or the like. As shown the said plate extends across the slotted portion *e*. By means of the said plate the needle *b* is prevented from 70 getting out of the slot *e* of the jack at one side thereof, the plate of the adjacent jack which is disposed close to the rear face of the jack preventing the needle from getting out of the slot at the opposite side. This 75 construction will preferably be provided where the pitch of the needles is small.

In the example shown in Figs. 5 and 6 at both sides of the jack *a* plates *c* and *c'* are provided which extend over the slotted part 80 *e* of the upper arm *a'*. This construction will be provided where the pitch of the needles is large, so that there is sufficient space for providing two plates between adjacent jacks. As in this construction two 85 plates are provided between adjacent jacks, the jacks can not be disposed so closely together as in the example shown in Figs. 1 to 4.

In both examples the plates are made in 90 separate pieces which are secured to the jacks by riveting. But I wish it to be understood, that my invention is not limited to this feature.

I claim:

1. The combination of a rocking jack of a circular knitting frame, a needle projecting into the slotted upper arm of said jack, and a plate fixed on the side of said arm extending across the slot to prevent lateral 100 movement of the needle.

2. The combination of a plurality of rocking jacks of a circular knitting frame, a needle projecting into the slotted upper arm

of each jack, and a plate fixed on one side only of each arm and extending across the slot thereof, said jacks being mounted in such close proximity to each other that the 5 plates of adjacent jacks will prevent lateral movement of the needles in either direction.

In testimony whereof I hereunto affix my

signature in the presence of two witnesses, this third day of March 1914.

ALBIN ERNST.
